Inventor:
James L. Gillard,
by Wallace R. Lane

UNITED STATES PATENT OFFICE.

JAMES LEONARD GILLARD, OF MUSKEGON, MICHIGAN, ASSIGNOR TO THE ALASKA REFRIGERATOR COMPANY, OF MUSKEGON, MICHIGAN, A CORPORATION OF MICHIGAN.

MEANS FOR SHOWING WALL FILLINGS.

Application filed December 24, 1923. Serial No. 682,594.

To all whom it may concern:

Be it known that I, JAMES L. GILLARD, a citizen of the United States, residing at Muskegon, Michigan, have invented a Means for Showing Wall Fillings, of which the following is a specification.

The subject-matter of this invention is designed primarily for showing, indicating or displaying the filling material of refrigerator walls, but it is conceivable that it may be used for other like purposes and it is, therefore, desired not to limit it to the specific use illustrated in the annexed drawing in which Fig. 1 is a fragmentary, 10 broken, perspective of a portion of a refrigerator; Fig. 2 is a longitudinal section of the displaying means; Fig. 3 is a perspective view of the inner end of the displaying means showing the use of a transparent plate of such material as glass or celluloid, or the like; and Figs. 4 and 5 show similar views in which other closure plates are used for this end of the display device.

Referring more in detail to the annexed drawing, numeral 1 denotes a side wall and 2 a front wall of a refrigerator R within the walls of which is a filling material 3, the purpose of which is to serve as a heat insulator. I prefer to use fragments of cork 25 for this filling material, though the precise substances for this purpose is immaterial so far as this invention is concerned.

Through a wall, such as the wall 2, of the refrigerator there is formed an opening for the reception of a tubular member 4 which is fastened in place by any suitable means. In the present instance this means comprises the refrigerator name plate 5 which is perforated to display an end of the tubular 35 member.

At its ends, the tubular body is provided with inwardly and outwardly extending flanges 6 and 7, though other means may be provided for supporting the end closure members 8 and 9. A transparent closure plate 10 of wire netting or similar material may, if desired, be substituted for the plate 8, or other material such as a metal plate 11 may be used at this end of the tubular member, though celluloid or mica is preferred. For the outer end, material of the general

nature of thin sheet celluloid is considered preferable.

With this construction the filling material of the refrigerator walls may be displayed to a prospective purchaser without in any way injuring the original finish of the refrigerator wall. Furthermore, if the covering plate 9 is broken, accidentally or otherwise, the plate 8 will prevent the contents of the refrigerator wall from sifting out through the cartridge, thus leaving the refrigerator improperly insulated. That is, the plate 8 will keep the refrigerator properly insulated even though the plate 9 should be broken. Also, use of a transparent plate 8 avoids the necessity of removing the cartridge to show that the packing material in the wall is the same as that in the cartridge in event some purchaser should be 55 skeptical concerning this point. Also, the flange 7 serves not only as means for supporting the plate 8 but also as a means for holding the same in place and preventing it from being easily slipped off from the end of the tube. This is due to the fact that the plate 9 has projections or tongues 12 which extend around the flange 7 and are secured in place by any desired means 13.

It is, of course, understood that the specific description of the structure set forth above may be departed from without departing from the spirit of my invention as set forth in the specification and the appended claims.

Having now described my invention, I claim:

1. In combination with a wall having filling material therein, a display means comprising a capsule having a transparent portion for viewing purposes.
2. The combination of a wall and a display means, the wall having filling means therein and the display means having a substantially rigid hollow body provided 95 with a transparent end.
3. The combination of a filled wall and means for indicating the filling material of the wall, said means comprising a tubular member extending from the surface of the wall into the interior thereof and containing 100 a portion of the filling material of the wall,

the outer end of the tubular member having a transparent covering member.

4. The combination of a filled wall and means for showing the filling material of the wall, said means comprising a tubular member extending from the surface of the wall into the interior thereof and containing a portion of the filling material of

the wall, the ends of the tube having closure members connected therewith and the closure member at the outer end of the tube being transparent. 10

In witness whereof, I hereunto subscribe my name to this specification.

JAMES LEONARD GILLARD.

Certificate of Correction.

It is hereby certified that in Letters Patent No. 1,543,913, granted June 30, 1925, upon the application of James Leonard Gillard, of Muskegon, Michigan, for an improvement in "Means for Showing Wall Fillings," an error appears in the printed specification requiring correction as follows: Page 2, after line 12 insert the following as claim 5:

5. In a refrigerator, a wall having a heat insulating filling material in the interior thereof, in combination with a display device extending from the exterior to the interior of the wall, said device comprising a tubular member having a transparent closure at each end and a portion of the wall filling material in the interior thereof.; and that the said Letters Patent should be read with this correction therein that the same may conform to the record of the case in the Patent Office.

Signed and sealed this 18th day of August, A. D. 1925.

[**SEAL.**]

KARL FENNING,
Acting Commissioner of Patents.
